CLAIM

The ornamental design for an espresso dosing device, as shown and described.

DESCRIPTION

FIG. 1 is a perspective view of an espresso dosing device showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The broken lines in the drawing views represent unclaimed portions of an espresso dosing device, which are included for the purpose of illustrating unclaimed environment only, and form no part of the claimed design.
